COMBINATION GARMENT HANGER

Heinz Erran, Mount Vernon, N. Y.

Application June 29, 1946, Serial No. 680,343

4 Claims. (Cl. 223—88)

1

This invention relates to garment hangers, and more particularly to combination coat and trousers hangers, and aims to provide new and useful improvements whereby the hanger will support a coat in the usual way but at the same time will suspend a pair of trousers in a secure and positive manner so that there is no danger of the trousers slipping out and falling to the floor.

Another object of the invention is the provision of a two-piece combination coat and trousers hanger adapted to support a coat in the usual manner and having a removable clamping member adapted to clamp and hold the trousers against the body of the hanger, in a secure and positive manner.

Still another object of the invention is the provision of a hanger such as stated, which is simple in construction, easy and quick in its mode of operation, and inexpensive in cost of manufacture.

The above and other objects will become apparent in the following description, wherein characters of reference refer to like-numbered parts in the accompanying drawing. It is to be noted that the drawing is intended for the purpose of illustration only, and that it is neither desired nor intended to limit the invention necessarily to any or all of the exact details of construction shown excepting insofar as they may be deemed essential to the invention.

Referring briefly to the drawing,

Fig. 1 is a front elevational view of the combination hanger.

Fig. 2 is a plan view of the same.

Fig. 3 is a sectional view taken on the line 3—3 of Fig. 1.

Fig. 4 is a front elevational view of the detachable resilient clamping member per se.

Referring in detail to the drawing, the numeral 10 indicates a coat hanger formed of any suitable material, such as, for instance, metal, plywood, or a suitable plastic like Lucite, having the triangular body 11 and the hook 12 by means of which the hanger may be suspended from a pole 13.

Near each end of the body 11 an opening 14, rectangular in outline, is provided through the body. Intermediate the length of the hanger, a pair of vertically spaced parallel cuts 15 and 16 are made through the body, and the strip 17 thus cut out is bent, deformed, bowed or bulged rearward substantially as shown.

A separate trousers supporting member 18 comprises a resilient strip of suitable material, such as those mentioned, having the two extremities

2

thereof bent to form oppositely-extending noses 19 and 20 joined to the body of the strip 18 by the portions 21 at right angles to both the noses 19 and 20 and the body 18. It is to be noted that the nose 19 is longer than the nose 20. Intermediate the length of the strip 18, it is bulged forward at 22, complementarily to the bulge 17.

The manner of placing a coat on the hanger is obvious. The trousers are held with the cuffs 10 between the body 11 and the member 18. With the trousers held against the body at that level, the member 18 is set in place by first slipping one nose, that shown at 19, into the hole 14 on the left side, then sliding the member to the left until the section 21 registers against the wall of the opening; then the member 18 is bent or urged against the cuffs to bring the nose 20 through the opening 14 on the right, it being noted that the dimensions and shape of the openings are both equal to the dimensions and shape of the nose 20. When the nose 20 is thus pushed through the opening 14 on the right, thereby clamping the trousers between the member 18 and the body 11, the member 18 is then grasped by the bulge 22 and slid to the right until the nose 20 is positioned securely beyond the right-hand wall of the opening 14. The trousers are then firmly clamped against the body 11. The cuffs, not shown, of the trousers will rest on the upper edge of the bulge 22 as well as enter into the space left by the deformed strip 17 in the body 11; thus, the cuffs will be positively supported, in addition to be frictionally clamped, and thereby will be safe from falling.

Obviously, modifications in form and structure may be made without departing from the spirit and scope of the invention.

I claim:

1. A combination coat and trousers hanger comprising a flat sheet-like unitary substantially triangular body formed of substantially rigid material, said body having a hook thereon and being adapted to have a coat draped thereover, said body having spaced rectangular openings therethrough at the ends thereof, a resilient strip of substantially the same width as the height of said openings, said strip having the extremities thereof deformed to provide aligned outwardly extending noses, said openings having substantially the same length, one of said noses being of greater length than the other and of greater length than the length of said openings, the other of said noses being of substantially the same length as the length of said openings, said strip being adapted to clamp trousers between said

3

body and strip by insertion of said longer nose into one of said openings with said longer nose extending beyond the end wall of said one of said openings, then swinging the other end of the strip toward the body and forcing said shorter nose through the other of said openings and sliding said strip in the direction of said other of said openings until said shorter nose extends beyond the end wall of its said opening, the intermediate portion of said strip being thereby positioned on one side of said body.

2. The combination hanger set forth in claim 1, said strip having a bulge intermediate its length, said bulge extending in a horizontal direction outward from said one side of said body. 15

3. The combination set forth in claim 1, said body having a longitudinal strip cut out thereof intermediate its length, said last named strip being bowed horizontally outward on the other side of said body.

4. The combination hanger set forth in claim 1, said strip having a bulge intermediate its length, said bulge extending in a horizontal direction outward from said one side of said body said body having a longitudinal strip cut out thereof intermediate its length, said last-named strip being bowed outward horizontally on the other side of said body.

HEINZ ERRAN.
